METHOD AND MEANS FOR USE IN LASTING
SHOES

Fred N. La Chapelle, Beverly, Mass., assignor to
United Shoe Machinery Corporation, Paterson,
N. J., a corporation of New Jersey

Application June 8, 1936, Serial No. 84,017

51 Claims. (Cl. 12—2)

This invention relates to shoemaking, and in some aspects more particularly to improvements in methods and means for use in lasting shoes. The invention is herein illustrated by reference 5 to the lasting of an upper successively in different locations along the edge of the shoe bottom, and also by reference to that type of shoe in which the sole or other shoe bottom part (hereinafter frequently referred to generically as the 10 sole) is provided with a lip or shoulder to which the upper is fastened in lasted position, although it is to be understood that in these and other respects the invention in its more general aspects is not limited to the illustrated disclosure.

15 The present invention in one important aspect provides an improvement in methods of making shoes especially in regard to the manner of fastening the upper to the sole in the lasting operation. Shoes of the type above referred to are 20 frequently provided with soles having an inside channel to receive the upper-attaching seam and with an outer channel formed to provide an upper-attaching shoulder; and in accordance with the novel method of this invention, in one aspect, 25 portions of the upper are fastened to this shoulder in the lasting operation by paper fastenings, shown as staples, i. e., for example, fastenings of the character disclosed in United States Letters Patent No. 1,957,216, granted May 1, 1934, upon 30 an application of mine. More particularly, as herein shown, the upper is pulled successively in different locations to subject it to lasting strain, and while it is held under strain in each location fastening-receiving holes are formed in the upper and the sole and a paper staple is inserted 35 into these holes to fasten the upper initially yet permanently to the sole. Since the fastenings are made of paper they may accordingly be inserted in the upper and the sole substantially 40 in the line of the upper-attaching seam without any danger of objectionable results from interference between the needle, or the thread, and the lasting fastenings in the subsequent sewing operation. The fastening-receiving holes are 45 preferably formed in the body of the sole in locations below the inside channel so that the staples when inserted into the holes will hold the upper flat upon the margin of the sole without any substantial relaxing of the lasting 50 strain by reason of the fact that the crossbars will extend lengthwise of the edge of the sole close to the junction of the angle formed by the margin of the sole and the shoulder.

In a further important aspect, the invention 55 has in view the fastening of the upper in the

lasting operation to a lip on a sole by a staple inserted through the upper and the lip. As herein illustrated, holes are formed in the upper and the lip and a paper staple is then inserted in the holes and the legs clinched on the lip. 5 As further herein shown, the legs clinched on the inner face of the lip are also bent to conform to the angle formed by the lip and the body of the sole. Among other advantages, this serves substantially to avoid danger that the 10 staple will become loosened in the lip by the outward pull of the upper thereon, and since the lip is well adapted to withstand the strain of the upper, the upper is held effectively in lasted position. Preferably, as illustrated, the legs of the 15 paper staple are clinched on the inner face of the lip by the use of a clinching tool which is utilized to support the lip adjacent to the overlaid margin of the upper and which moves toward the sole to clinch the legs of the staple in a direction 20 inclined toward the inner face of the lip so that the legs of the paper staple are also flattened against the inner face of the lip and against the body of the sole as they are forced into the inside channel, thus affording further insurance that 25 the staple will not be loosened in the lip by the strain of the upper thereon. Moreover, the presence of the staple legs in the inside channel involves no danger of damage to the needle of the 30 sewing machine in the later operation of sewing the upper to the sole.

It is contemplated that the invention in its different novel aspects will have important advantages in its application to the manufacture of turn shoes, where the upper is lasted wrong 35 side out and is fastened to a shoulder or lip on the sole and then after being stitched is turned right side out, and of welt shoes where the insole is provided with an upper-attaching shoulder or lip, and accordingly it is herein illustrated as applied to the manufacture of these two kinds of shoes, but it is to be understood that it is not thus limited but presents advantages also as applied to the manufacture of other kinds of shoes, for example shoes of that type where 45 the insole is provided with an upper-attaching lip and the outsole is attached by cement, or by through-and-through stitching to the overlasted margin of the upper.

In a further aspect the invention provides a 50 novel organization of means especially adapted for use in the practice of the above-described method. For the purpose in view, the illustrated machine is provided with means for pulling an upper successively in different locations along 55

the edge of the last bottom and for laying the marginal portion of the upper inwardly over a sole and against a lip or shoulder on the sole, and mechanism automatically operative at the 5 end of each overlaying operation to form holes in the upper and the sole and to insert a fastening, illustrated as a staple, into the holes to fasten the upper in lasted position. As herein shown, the upper is pulled over the last by a 10 gripper and the lasting margin of the upper is laid inwardly over the sole and against the lip or shoulder on the sole by a nozzle or guide for the staples. The nozzle is mounted on a carrier that is movable in a direction inclined toward 15 the bottom of the last to impart to the nozzle its overlaying movement, the nozzle being provided with a guiding passage for the staples along which there is movable a driver for driving the staples from the nozzle after the nozzle has completed its inward movement. For forming the 20 holes in the upper and the sole to receive the legs of the staple there are provided awls which are mounted on the carrier and are movable relatively to the nozzle in passages formed in 25 the carrier at a slight angle to the direction of movement of the driver, these passages being arranged to intersect the staple passage in the nozzle at the outlet end of the nozzle. For imparting to the awls their work-penetrating movement there is provided a spring against the 30 resistance of which the awls are held initially in a retracted position by mechanism which is arranged to release the spring after the nozzle has completed its inward movement and to return 35 the awls to their initial position prior to the staple-driving operation.

The invention further provides novel means for clinching the legs of the staple. For operating on work in which the fastenings are driven 40 through the upper and a lip on the sole, the machine is provided with a sole rest arranged to position the shoe by engagement with the lip. In the construction shown, the sole rest is slotted to provide clearance for the awls and to receive 45 the legs of the staples and means, illustrated as a clinching tool, is provided for clinching the legs of the staple on the inner face of the lip and for also bending them to conform to the angle formed by the lip and the body of the sole. 50 Preferably and as illustrated, the clinching tool is arranged to extend initially into the slot formed in the sole rest in position to support the lip in the overlaying operation, and mechanism is provided for moving the tool out of engagement with 55 the lip prior to the operative movement of the awls and for moving the tool toward the sole to clinch the legs of the staple at the end of the driving operation, this movement of the tool being preferably in a direction inclined toward the 60 inner face of the lip to cause the legs of the staple to be flattened against the lip and being also preferably of such extent that the legs of the staple are also compressed between the body of the sole and the tool.

65 In addition to its novel method and machine aspects the invention further presents novelty in a shoe having its upper fastened to the lip on a sole by staples the legs of which are clinched on the inner face of the lip and are also bent to 70 conform to the angle formed by the lip and the body of the sole. Not only is the upper thus held securely in lasted position, thereby insuring a tightly lasted shoe, but with the ends of the staple legs located in the inside channel and bent

75 into the angle formed by the lip and the body of the sole there will be no danger of their penetrating the inside face of the finished shoe. The invention provides further novelty in a shoe having a sole to which the margin of the upper along its opposite sides is secured in lasted condition by paper staples driven through portions of the upper subjected to strain in the lasting operation and a lip on the sole with the legs of the staples clinched on the inner face of the lip 10 and flattened against said face. With the legs of the staples flattened against the inner face of the lip further assurance is afforded that they will not become loosened in the lip by the strain of the upper thereon. The invention provides 15 still further novelty in a shoe having a shouldered sole provided with an inside channel to which the margin of the upper along the opposite sides of the shoe is secured in lasted condition by paper staples driven through portions of the upper subjected to strain in the lasting operation and into the sole in locations below said inside channel with the cross bars of the staples extending lengthwise of the sole close to the junction of 20 the shoulder and the margin of the sole. 25

The above and other features of the invention including various novel details of construction and combinations of parts, and also the method in its various novel aspects, will now be more particularly described by reference to the accompanying drawings, and thereafter pointed out in the claims.

In the drawings,

Fig. 1 is a view in right-hand side elevation of 35 the head of a lasting machine adapted for use in practicing the novel method and illustrating one embodiment of the novel features of the invention;

Fig. 2 is a view in left-hand side elevation on an 40 enlarged scale of a portion of the upper-tensioning and fastening-inserting mechanisms and the hole-forming means with the parts in the positions that they assume when the machine is at rest;

Fig. 3 is a section on the line III—III of Fig. 1;

Fig. 4 is a section on the line IV—IV of Fig. 2;

Fig. 5 is a perspective view with parts broken away of a portion of the upper-fastening mechanism, showing the relative positions of the awls and the nozzle member when the machine is at 50 rest;

Fig. 6 is a view in right-hand side elevation of the head of the machine shown in Fig. 1, but provided with a different sole rest and with mechanism for clinching the legs of the staples; 55

Fig. 7 is a view in left-hand side elevation on an enlarged scale of portions of the upper-tensioning, fastening-inserting and hole-forming mechanisms and the clinching means with the parts in their initial positions;

Fig. 8 is a view looking in the direction of the arrow A in Fig. 7 with parts broken away to show more clearly the construction of portions of the mechanism for operating the clinching tool;

Fig. 9 is a view illustrating the positions of the nozzle and the sole rest at the time of driving the staple in lasting a turn shoe provided with a shouldered sole;

Fig. 10 shows the same parts as Fig. 9 in their relative positions at the time of driving a staple in lasting a Goodyear welt shoe having a shouldered insole;

Fig. 11 is a view illustrating the positions of 75

the clinching tool and other parts, at the end of the overlaying operation, in operating on a turn shoe in which the marginal portion of the upper is to be fastened to a lip on the sole;

5. Fig. 12 shows the same parts as Fig. 11 at the end of the clinching operation;

Fig. 13 is a view similar to Fig. 12 showing the clinching of the legs of the staple after it has been inserted through the upper and the lip of 10 the insole of a Goodyear welt shoe;

Fig. 14 is a cross sectional view of a portion of a turn shoe of the type shown in Fig. 9 after the upper has been further secured to the sole by a thread seam; and

15. Fig. 15 is a cross sectional view of a portion of a turn shoe of the type shown in Fig. 12 after the sewing operation.

Since the general features of the type of lasting machine herein shown are described in Letters Patent of the United States No. 1,796,451, granted on March 17, 1932, on an application of George Goddu, only such portions of the illustrated machine as it is necessary to refer to for a complete understanding of the present invention in its machine aspects will be herein described in detail.

As more fully described in the above-mentioned Letters Patent, the machine herein shown includes in its organization a gripper comprising jaws 23 which are operated to grip and pull the upper heightwise of the last and inwardly over the sole in different locations successively along the edge of the last bottom as the operator presents and holds the shoe in different positions 35 for successive lasting operations. In one form of the machine the shoe is supported against the pull of the gripper and is positioned in proper relation to the different operating instrumentalities by a sole rest member 22 which engages the 40 sole on the inner face of a lip *a* and, in operating on work of the type illustrated, extends into the inner channel adjacent to the lip.

For laying the marginal portion of the upper inwardly over the sole in time relation to each 45 upper pulling operation of the gripper there is provided an overlaying device comprising a staple-guiding nozzle 24 supported as described in the previously-mentioned Letters Patent on a slide 26 which is movable along guideways 23 50 (Fig. 2) provided by a bracket 36 fast on the head of the machine. These guideways are inclined in such relation to the shoe positioned and held as above described that the nozzle 24 engages the upper initially a substantial distance 55 above the sole and moves in a direction inclined toward the bottom face of the last in laying the upper inwardly over the sole. The nozzle 24 is provided with a guideway 32 for the staple *s*, the staple being supported for movement in the 60 guideway by a staple guiding face 34 (Figs. 2 and 5) on a member 36 secured to a bracket 33 carried by the slide 26. The staple is driven by a driver 40 movable along the face 34 and the guideway 32 and carried by a slide 42 mounted 65 in guideways formed by the bracket 33 and the slide 26 (Fig. 4). The driver is operated by a swinging arm 44 which, in the construction herein shown, is pivoted at its upper end on a stud 46 on the slide 26 and at its lower end has a 70 bearing in a recess formed in the slide 42, the arm being operated by a torsion spring 48 (Fig. 2). To tension the spring and to retract the driver, the arm 44 is held back by a latch 50 when the slide 26 is moved forwardly to cause 75 the nozzle 24 to lay the upper over the sole, the

latch being carried by a lever 52 which is operated after the forward movement of the slide 26 to cause a screw 54 on the slide to disconnect the latch from the arm 44 and thus release the arm to the action of the spring 48. Carried also by 5 the slide 26 is an outside former comprising plates 56 which cooperate with a stationary inside former 58 to form a staple in the forward movement of the slide. The staple is thus formed in a location above the path of movement of the 10 driver 40 and must accordingly be transferred to a position in alignment with the driver. For this purpose the plates 56, which have in their inner faces recesses of less depth than the thickness of the stapling material and in which the legs 15 of the staple lie when they are formed, are carried by a slide 60 which is movable downwardly at the end of the overlaying and staple forming operations to carry the staple to a position in which it rests on the guiding face 34. It is at this 20 point in the operation that the staple is driven, as hereinabove described.

The machine herein shown is provided with means for feeding fiber fastening material 62 (Fig. 1) from a reel 64, the feeding means comprising feed rolls 66, 68, the latter being pressed against the former by spring means indicated at 70 (Fig. 1). The feed rolls 66, 68 are operated to feed the fastening material by mechanism which is substantially the same as that shown and described in the prior Letters Patent. After the fastening material leaves the feed rolls it passes through a guiding tube 72 by which the fastening material is directed through a guide block 74 (Fig. 2) to the fastening-severing and staple-forming instrumentalities of the machine. It will be understood that the feed rolls 66, 68 are operated intermittently to feed the fastening material in definite amounts, and the fed-in portion of material is severed by a cutter 76 in the forward 40 movement of the slide 26, after which the severed portion of the fastening material is formed into a staple by the relative movement of the outside and inside formers 56, 58 in the continued 45 forward movement of the slide 26. For a more 50 complete understanding of the construction and manner of operation of the parts thus far described reference may be made to the previously 55 mentioned Letters Patent.

The illustrated machine is provided with mechanism which will now be described for forming fastening-receiving holes in the work to receive the legs of the staples. Slidably mounted on guideways 78 on the member 36, below the driver slide 42 (Figs. 2 and 4), is an awl bar 80 to 60 which there is secured by a clamp 82 a pair of awls 84 which are arranged to reciprocate in guiding passages 86 formed in the forward portion of the member 36. The guiding passages are formed in the member 36 at a slight angle to the 65 direction of movement of the driver 40 and are arranged to intersect the guideway 32 in the nozzle 24 at the extreme forward or outlet end of the nozzle so that the entering ends of the holes formed in the work by the awls 84 will be in the 70 line of drive of the legs of the staples as they are driven into the work by the driver 40. As the awls are driven into the work they are supported by the nozzle 24, plates 85 being provided, which 75 are fastened to the member 36, one at each side, for confining the awls within the guiding passages 86 rearwardly of the nozzle member. At their rear ends the awls 84 engage an abutment 88 on the awl bar 80. For operating the awl bar 80 there is provided an arm 90 (Figs. 1 and 3) which 80

at its upper end is keyed to a rock-shaft 92 supported in suitable bearings in the head of the machine. Pivotedly connected to the lower end of the arm 90 is a member 94 threaded into a rod 96 which extends forwardly and is pivotally connected to the awl bar at 98. The arm 90 is operated to impart work-penetrating movement to the awls 84 by a torsion spring 100, one end of which is connected to a member 102 which may be turned to adjust the tension of the spring and is held in adjusted position by a pin 104 which extends through a flange 105 on a bearing cap 106 fast to the head of the machine, the pin 104 being arranged to enter any one of a series of holes 108 formed in the member 102. The rod 96 (Fig. 1) extends through an enlarged opening in a boss 110 formed on a bracket 112 fast to the head of the machine. For limiting the driving movement of the arm 90 there is provided a split collar 114 which is threaded on the rear end portion of the rod 96 and is arranged to engage one of three fiber washers 116 mounted on the rod 96 between the split collar 114 and the boss 110. It will be understood that the collar 114 may be adjusted lengthwise of the rod 96 to vary the extent of driving movement of the arm 90 and, accordingly, the depth to which the awls 84 penetrate into the work, a screw 118 being provided for effecting relative movement of the two parts 30 of the split collar to hold it in adjusted position.

Fast to the rock-shaft 92 is a second arm 120 to the lower end of which is pivotally connected a bar 122 carrying a member or block 124 arranged to engage the periphery of a cam wheel 126 fast to the main cam shaft 128 mounted in suitable bearings in the head of the machine. The bar 122 is supported and positioned with the member 124 in engagement with the periphery of the cam wheel 126, by a block 130 rotatably mounted on the cam shaft 128 and engaging a guideway 132 formed in the forked end 134 of the bar 122. The periphery of the cam wheel 126 is such that at a predetermined time in the operation of the machine, as more fully herein-after explained, the arm 90 is released to the action of its operating spring 100 to impart work-penetrating movement to the awls 84.

As previously pointed out, the staple s is transferred from forming position into alinement with the driver 40 by downward movement of the slide 60 at the end of the forward movement of the slide 26. As the slide 26 completes its forward movement, the arm 90 is released to the action of the spring 100 to operate the awls 84 to form fastening-receiving holes in the upper and in the sole, the cam wheel 126 having its peripheral face so shaped that the bar 122 is moved rearwardly (Fig. 1) to swing the arm 120 and through the rock-shaft 92, the arm 90 in a direction to withdraw the awls from the work immediately after they have completed their work-penetrating movement and before the slide 60 has completed its downward movement to transfer the staple into alinement with the driver 40. It will be understood that the depth to which the awls 84 are driven into the work may be varied by adjustment of the split collar 114 on the rod 96 and that after the awls have been driven into the work, they are retracted into a position in which there will be no interference between them and the driver 40 as the driver moves along the guiding surface 34 and the guideway 32 to drive the staple from the nozzle 24 into the holes formed in the work by the awls. It will be evident that 75 the initial position of the awls relatively to the

nozzle 24 may be varied by adjustment of the rod 96 relatively to the member 94. For effecting a finer adjustment of the initial position of the awls, there is provided an eccentric stud 136 (Figs. 1 and 3) for connecting the member 94 to the arm 90, a nut 138 being provided for holding the stud in adjusted position.

In operating with this machine to side last a turn shoe having a relatively heavy sole provided with an upper-attaching shoulder b (Fig. 10 9), the work is held by the operator in engagement with the work rest 22. It is intended that the operator shall hold the work at an inclination to the horizontal somewhat less than the inclination of the driver 40 and that the work 15 rest 22 shall have been previously adjusted to position its sole-engaging end slightly above the guideway 32 in the nozzle 24 so that the fastening-receiving holes will be formed in the sole in locations below the inside channel. With the work 20 positioned as above described, the upper is pulled tightly over the last and inwardly over the sole by the gripper and its marginal portion is pressed into firm contact with the margin of the sole and with the upper-attaching shoulder b at 25 the junction of the latter with the margin of the sole by the nozzle 24. With the upper thus held by the nozzle 24, fastening-receiving holes are formed in the upper and in the body portion of the sole below the inside channel, after which a 30 paper staple is driven through the upper and into the sole to hold the upper firmly in lasted position.

It will be understood that these lasting operations are performed in different locations along 35 the sides of the shoe, the shoe being moved by the operator to present it in different positions for side lasting. It will be seen that, for the purpose in view, the upper is fastened initially yet permanently to the sole in each location where 40 the upper is subjected to lasting strain by a paper staple, the legs of which are located in the body portion of the sole below the inside channel with the cross-bar of the staple extending lengthwise of the edge of the sole close to the 45 junction of the margin of the sole and the upper-attaching shoulder. It will be evident by reference to Fig. 9 that with the staples inserted in the locations above described, the margin of the upper is held by the staples flat upon the margin of the sole, thereby facilitating the forming of a tight seam in the subsequent sewing operation whereby the upper is further fastened to the sole (Fig. 14). It will also be evident that because of the character of the staples, they may be 50 thus inserted with their cross-bars located substantially in the line of stitching without danger of breaking the needle of the sewing machine or 55 damaging the thread in the sewing operation.

In operating upon a turn shoe not provided with a shouldered sole, or where the thickness of the sole is such that there is danger that the awls will form undesirable irregularities in that surface of the sole which is outermost in the finished shoe if the fastening-receiving holes are formed in the body portion of the sole, it is contemplated that the upper may be fastened to the lip a of the sole. For this purpose, there is provided a work rest 140 (Figs. 7 and 8) which differs from the work rest 22 in having a central slot 141 formed in its sole-engaging end to provide clearance for the awls 84. Preferably, the work rest 140 when substituted for the work rest 22 will be adjusted so as to position the work 65 somewhat lower in the machine than the work 70 75

rest 22 to cause the upper in each location where the pull is applied to be pressed against the outer face of the lip in a location opposite the work rest 140 in the last part of the forward movement of the staple-guiding nozzle 24. By reference to Fig. 11 it will be seen that when the work is held by the operator in engagement with the work rest 140, the lip *a* is supported by the work rest, the end of the work rest being so shaped as to engage snugly in the angle or channel formed by the lip and the body of the sole. The work rest 140 (Figs. 7 and 8) is adjustably secured to a holder 142 which is loosely mounted on a shaft 144 mounted to turn in a sleeve 146 adjustably clamped by means of a screw 148 in a split bearing formed in the front end of the bracket 39. The sleeve 146 is provided with an arm 149 having its upper portion formed as a split bearing for a threaded stud 150, a screw 152 being provided for effecting relative movement of the two parts of the split bearing to bind the stud in adjusted position. Extending between the stud 150 and an upwardly extending finger 154 on the holder 142 in a spring 156 which tends to swing the holder in a direction to move the work rest 140 toward the nozzle 24, this movement of the holder being limited by engagement of the finger 154 with an adjustable screw 158 carried by a second arm 160 on the sleeve 146. By adjusting the screw 158 the work rest 140 may be positioned relatively to the nozzle 24 in accordance with the thickness of the shoe materials which are to be clamped by the nozzle and the work rest, a nut 159 being provided for holding the screw 158 in adjusted position. The spring 156 affords provision for yield of the work rest in accordance with variations in the thickness of the material at different parts of the shoe, but is of sufficient strength to hold the work rest firmly in position to support the lip *a* in hole-forming and fastening-inserting operations. As previously pointed out, the work rest 140 has a slot 141 formed in its lower end portion to provide clearance for the awls 84. This slot is in alignment with the staple-guiding passage 32 in the nozzle 24 and is arranged to receive the legs of the staple as it is driven by the driver 40 through the holes formed in the upper and the lip by the awls.

In order to increase the holding power of the staples, the illustrated machine is provided with means for clinching the legs of the staples on the inner face of the lip *a*. For this purpose, there is movable in a guideway formed in the work rest 140 in alignment with the slot 141 a tool 164 which is operated, as hereinafter described, to bend the legs of the staple, after they have been driven through the upper and the lip *a*, toward the bottom face of the sole and to force them into the inside channel of the sole. The tool 164 is substantially as wide as the slot 141 in the work rest and has an upwardly extending offset portion 166 slidably mounted in the holder 142 (Figs. 7 and 8). Adjustably secured to the upper end of the portion 166 is a plate 168 arranged by engagement with a finished surface 170 on the holder to prevent turning movement of the tool 164 in the holder. For operating the tool 164 there is provided a segment 172 having teeth 174 formed thereon arranged to engage rack teeth 176 formed on the upwardly extending portion 166 of the tool 164. The segment 172 is formed integral with or is secured to the shaft 144, and keyed to the shaft 144 is an arm 178 connected by an adjustable link 180 to the forwardly extend-

ing arm of a bell-crank lever 182 (Fig. 6) having a rearwardly extending arm 184 carrying a roll 186 engaging a path cam 188 formed in a cam wheel 190 fast to the shaft 128. The arm 178 is held against movement lengthwise of the shaft 144 by a shoulder 192 on the shaft and a washer 194 engaging another shoulder on the shaft and supported by a nut 196 threaded on the reduced end portion of the shaft. The cam 188 is so formed that downward movement toward the sole is imparted to the tool 164 to clinch the legs of the staple by upward movement of the forwardly extending arm of the bell-crank lever 182 and upward movement away from the sole is imparted to the tool by downward movement of the arm. The tool 164 is arranged to extend initially into the slot 141 in the work rest 140 in position to support the lip of the sole during the overlaying operation (Fig. 11), the shape of the cam 188 being such that the tool 164 is moved upwardly out of engagement with the lip prior to the operative movement of the awls and is operated to clinch the legs of the staple after the driver 40 has completed its driving movement and before the nozzle 24 is retracted. The upper and lip are accordingly held clamped against the work rest 140 by the nozzle during the clinching operation and since the driver 40 is at this time in driving position, the cross-bar of the staple is supported by the driver, thereby effecting a tight clinching of the staple. By reference to Figs. 11 and 12, it will be seen that the tool 164 moves toward the bottom face of the sole to clinch the legs of the staple in a direction inclined toward the inner face of the lip *a*. As the tool moves downwardly, it also bends the ends of the legs of the staple to conform to the angle formed by the inside face of the lip and the body of the sole and compresses the legs somewhat against the lip *a* and the sole, thereby increasing their holding power and affording further insurance that they will not be loosened in the work by the strain of the upper thereon. Fig. 12 shows the operation of clinching the legs of the staples on the inside face of the lip *a* and also bending them into conformity to the angle formed by the lip and the body of the sole.

It will be understood that before the shoe is side lasted, whether the staples are inserted in the location shown in Fig. 9, or through the upper and the lip *a* of the sole, the shoe may have been previously lasted at the toe end portion, and that after the toe and side-lasting operations have been performed, the upper is further secured to the sole by a thread seam *t* (Figs. 14 and 15). After the sewing, the margin of the upper is trimmed and the last is withdrawn from the shoe. The shoe is then turned and mounted on a second last, after which the heel end of the shoe is lasted and the remaining manufacturing operations are performed as usual. If the shoe is of the type shown in Fig. 12, it will be evident that there is no danger of blunting the point of the needle or of other damage if the ends of the legs of the paper staples that extend into the inside channel of the sole are hit by the needle in the sewing operation. Moreover, in operations performed after the shoe has been mounted on the second last, for example, in applying leveling pressure to the sole, the paper staples will be compressed as the lip *a* and the margin of the upper are pressed close to the body of the sole so that no objectionable projections or ridges will be formed in the inner face of the sole. If the shoe is of the type shown in

Fig. 9, the upper is held in lasted position closely adjacent to the edge of the sole for the operation of the sewing machine without any danger of damage if one of the staples is accidentally hit by the needle of the sewing machine.

While the invention has been described with particular reference to the manufacture of turn shoes, it will be recognized that, in some features, it is not thus limited but is applicable to the manufacture of other types of shoes, for example, Goodyear welt shoes. The term "sole" as used in the claims is therefore not to be construed as limited to the single sole of a turn shoe, but as applicable generally to that shoe bottom part over which an upper is lasted, including the insole of certain types of shoes.

Fig. 10 illustrates the operation of fastening the upper of a Goodyear welt shoe in lasted relation to a shouldered insole by a paper staple *s*. The insole is provided with an inside channel to receive a thread seam for sewing the upper and the welt to the sole and with an outside channel formed to provide an upper-attaching shoulder to which the upper is secured by a staple in each lasting location after the marginal portion of the upper has been forced into the angle formed by the shoulder and the margin of the sole by the nozzle *24*. In each lasting location, the shoe is positioned by the sole rest *22* in such relation to the different operating instrumentalities that the fastening-receiving holes are formed in the upper by the awls *84* and in the sole below the inside channel.

Fig. 13 illustrates the step of fastening the upper of a Goodyear welt shoe to the lip of an insole by a paper staple *s*, the legs of which are clinched on the inner face of the lip and are bent to conform to the angle formed by the lip and the sole and are also flattened against the lip and the sole by the clinching tool *164* to insure that the staple will not be loosened in the work by the strain of the upper thereon.

It will be evident that substantially the same advantages that apply to the manufacture of turn shoes apply also to the manufacture of Goodyear welt shoes by the practice of the method herein disclosed. The paper staples are conveniently and preferably driven in the best possible locations to hold the upper most effectively in lasted condition, that is to say, they are driven in locations closely adjacent to or in the line of the upper and welt-attaching seam without any danger that the needle of the sewing machine will be broken or the thread cut or injured by striking one of the paper staples so that substantial assurance is afforded that a perfect inseam will be formed. Moreover, since in the manufacture of Goodyear welt shoes the surplus margin of the upper and the welt are trimmed substantially to the plane of the bottom face of the sole, after the inseam sewing operation, the use of paper staples avoids any danger of damaging the knife of the trimming machine.

Having described my invention, what I claim as new and desire to secure by Letters Patent of the United States is:

1. A lasting machine having, in combination, means for pulling an upper over a last successively in different locations along the edge of the last bottom and for laying the marginal portion of the upper inwardly over a sole on the last and against a shoulder on the sole, and mechanism automatically operative at the end of each over-laying operation to form holes in the upper and the sole in a location close to the apex of the

angle formed by the shoulder and the margin of the sole and then to insert a staple into said holes to fasten the upper in lasted position.

2. A lasting machine having, in combination, means for operating successively in different locations along the side of a shoe to tension the upper over a last and to lay its marginal portion inwardly over a sole on the last and against a lip or shoulder on the sole, and means for forming holes in the upper and the sole in each of said locations while the upper is held in lasted position and for inserting a paper staple into the holes formed in the upper and the sole to fasten the upper in lasted position.

3. In a lasting machine, the combination with means for pulling an upper over a last successively in different locations along the edge of the last bottom and for laying the marginal portion of the upper inwardly over a sole on the last and against a shoulder on the sole, and means constructed and arranged to operate in time relation to said first-named means for inserting fastenings through the upper and into the sole, of means for forming fastening-receiving holes in the upper and the sole in each location prior to the insertion of a fastening.

4. In a lasting machine, the combination with means for pulling an upper over a last, and upper-fastening mechanism movable inwardly over the bottom of the last to lay the marginal portion of the upper over a sole on the last and against a lip or shoulder on the sole, said upper-fastening mechanism comprising means for driving a fastening through the upper and into the sole, of means movable independently of the movement of said upper-fastening mechanism for forming holes in the upper and the sole for the reception of the fastening.

5. In a lasting machine, the combination with means for pulling an upper over a last successively in different locations along the edge of the last bottom and for laying the marginal portion of the upper in each location inwardly over a sole on the last and against a projection on the sole, and means for driving a paper staple through the upper and into the sole in time relation to each overlaying operation, of a pair of awls for forming holes in the upper and the sole to receive the legs of each staple, and automatic means for operating said awls to form the fastening-receiving holes in time relation to each overlaying operation and for retracting said awls prior to each staple-driving operation.

6. A lasting machine having, in combination, means for pulling an upper over a last having a sole thereon, upper-fastening mechanism movable inwardly over the bottom of the last to lay the marginal portion of the upper over the sole and against a shoulder on the sole, said upper-fastening mechanism comprising a nozzle member having a fastening-guiding passage therein and a driver for driving a fastening from said nozzle member, and means for perforating the upper and the sole prior to the fastening-driving operation.

7. A lasting machine having, in combination, means for pulling an upper over a last having a sole thereon, upper-fastening mechanism movable inwardly over the bottom of the last to lay the marginal portion of the upper over the sole and against a shoulder on the sole, said upper-fastening mechanism comprising a nozzle member having a fastening-guiding passage therein and a driver for driving a fastening from said nozzle member, and means for forming fastening-

receiving holes in the upper and the sole in alignment with the outlet end of said nozzle member prior to the fastening-driving operation.

8. A lasting machine having, in combination, 5 means for pulling an upper over a last having a sole thereon provided with an upper-attaching shoulder, an overlaying device movable inwardly over the bottom of the last in a direction inclined toward its bottom face to force the marginal portion of the upper into the angle formed by the shoulder and the margin of the sole, said overlaying device having a staple-guiding passage therein, means for driving a paper staple from said overlaying device, and means movable 10 relatively to the overlaying device at the end of its overlaying movement for forming holes in the upper and the sole to receive the legs of the staple in the driving operation.

9. A lasting machine having, in combination, 20 upper-fastening mechanism movable inwardly over the bottom of a last successively in different locations along the edge of the last bottom to lay the marginal portion of the upper over a sole on the last and against a lip or shoulder on the sole 25 and to drive a fastening through the upper and into the sole to fasten the upper in lasted position in each location, and means for forming holes in the upper and the sole in each of said locations prior to the driving of a fastening.

30 10. A lasting machine having, in combination, means for pulling an upper over a last having a sole thereon, and upper-fastening mechanism movable inwardly over the bottom of the last to lay the marginal portion of the upper over the 35 sole and against a shoulder on the sole, said upper-fastening mechanism comprising means for forming a paper staple, a driver for driving the paper staple through the upper and into the sole, means for transferring the paper staple from 40 forming position into alignment with the driver, and a pair of awls for forming holes in the upper and the sole to receive the legs of the staple.

11. A machine for lasting a turn shoe having a sole provided with an inside channel and an upper-attaching shoulder comprising, in combination, 45 means for pulling the upper and for forcing it into the angle formed by the margin of the sole and the upper-attaching shoulder, means for forming holes in the upper and the sole, means for driving a fastening into said holes to fasten the upper to the sole, and a sole rest arranged to engage the sole in said inside channel and to position the shoe relatively to said hole-forming means to cause the holes to be formed in the sole 50 below said inside channel.

12. In a lasting machine, an upper-fastening device movable in a direction inclined toward the bottom face of a last into position for inserting a fastening to fasten the marginal portion of an upper to a sole on the last, said device comprising 55 a staple-guiding nozzle and a driver movable to drive a staple from said nozzle through the upper and into the sole, and means for forming holes in the upper and the sole for the reception of the staple after said device has been moved into upper-fastening position and prior to the operative movement of the driver.

13. In a lasting machine, an overlaying device movable inwardly over the bottom of a last to 60 lay the marginal portion of an upper over a sole on the last and against a shoulder on the sole, a pair of awls for forming fastening-receiving holes in the upper and the sole, and a driver for driving a staple into said holes to fasten the upper to the 65 sole, said overlaying device having a driver pas-

sage formed therein and guiding passages for the awls, said guiding passages being arranged to intersect said driver passage at the outlet end of the passage.

14. In a lasting machine, an upper-fastening device movable in a direction inclined toward the bottom face of a last into position for inserting a staple to fasten the marginal portion of an upper to a sole on the last, said device comprising a staple-guiding nozzle, a driver, and means for operating the driver to drive a paper staple from said nozzle through the upper and into the sole, a pair of awls for forming holes in the upper and the sole to receive the legs of the paper staple, and means for operating said awls after said device has been moved into upper-fastening position and for retracting the awls prior to the operation of the driver.

15. In a lasting machine, upper-fastening mechanism movable inwardly over the bottom of a last to lay the marginal portion of an upper over a sole on the last and against a shoulder on the sole, said upper-fastening mechanism comprising means for driving a fastening through the upper and into the sole, and means movable relatively to said upper-fastening mechanism at the end of its inward movement for forming fastening-receiving holes in the upper and the sole prior to the fastening-driving operation.

16. In a lasting machine, the combination with 30 means for shaping an upper over a last having a sole thereon, and means for fastening the upper to the sole comprising a nozzle having a staple passage therein, a driver for driving paper staples from said nozzle through the upper and 35 into the sole, and a slide for supporting said nozzle and for moving it in a direction inclined toward the bottom of the last to lay the marginal portion of the upper over the sole, of a pair of awls supported by said slide and mounted for 40 movement relatively thereto to form holes in the upper and the sole to receive the legs of the paper staple, said slide being provided with guiding passages for said awls arranged to intersect said staple passage at the outlet end of said nozzle.

17. In a lasting machine, the combination with 45 means for shaping an upper over a last having a sole thereon, and means for fastening the upper to the sole comprising a carrier movable in a direction inclined toward the bottom of the last, an overlaying member mounted on said carrier for laying the marginal portion of the upper over the sole, and means for driving a fastening from said overlaying member through the upper and into the sole, of an awl bar slidably mounted on said 50 carrier, a pair of awls carried by said awl bar, and mechanism for reciprocating said awl bar between the overlaying and fastening driving operations to cause the awls to form holes in the upper and the sole for the reception of the fastening.

18. In a lasting machine, the combination with 55 means for shaping an upper over a last having a sole thereon, and means for fastening the upper to the sole comprising a carrier movable in a direction inclined toward the bottom of the last, an overlaying member mounted on said carrier for laying the marginal portion of the upper over the sole, and means for driving a fastening from said overlaying member through the upper and 60 into the sole, of a pair of awls for forming holes in the upper and the sole for the reception of the fastening, means for operating said awls comprising a spring, and a cam for retracting said awls and for tensioning said spring, said cam 65 70 75

being so shaped as to release said spring to render it operative at the end of the overlaying operation.

19. In a lasting machine, the combination with means for shaping an upper over a last having a sole thereon, and means for fastening the upper to the sole comprising a carrier movable in a direction inclined toward the bottom of the last, an overlaying member mounted on said carrier for laying the marginal portion of the upper over the sole, and means for driving a fastening from said overlaying member through the upper and into the sole, of a pair of awls for forming holes in the upper and the sole for the reception of the fastening, means for operating said awls comprising a spring-operated arm, and an adjustable stop for limiting the driving movement of said arm to determine the depth to which the awls penetrate into the work.

20. In a lasting machine, the combination with means for pulling an upper over a last successively in different locations along the edge of the shoe bottom and for laying the marginal portion of the upper in each location inwardly over a sole on the last and against a projection on the sole, and means for driving a staple through the upper and into the sole in time relation to each overlaying operation, of a pair of awls for forming holes in the upper and the sole to receive the legs of each staple, a spring for imparting to said awls their work-penetrating movement, and mechanism for holding said awls initially retracted and for releasing them at the end of each overlaying operation.

21. In a lasting machine, the combination with means for pulling an upper over a last successively in different locations along the edge of the shoe bottom, overlaying means movable toward the shoe to lay the marginal portion of the upper over a sole on the last and against a shoulder on the sole after each upper-pulling operation, and a driver for driving a staple through the upper and into the sole in time relation to each overlaying operation, of a pair of awls for forming holes in the upper and the sole to receive the legs of the staple, a spring for imparting to said awls their work-penetrating movement, and mechanism for holding said awls initially retracted against the resistance of said spring independently of the overlaying means, said mechanism being constructed and arranged to release the awls to the action of said spring after the overlaying means has completed its movement toward the shoe and to return said awls to their initial position after they have completed their work-penetrating movement and prior to the staple-driving operation.

22. In a lasting machine, the combination with means for pulling an upper over a last successively in different locations along the edge of the last bottom, of a device movable inwardly over the bottom of the last to lay the marginal portion of the upper over a sole and against a lip on the sole in time relation to each upper-pulling operation, means for driving a fastening through the upper and the lip in time relation to each overlaying operation, and means operative at the end of each driving operation to clinch each fastening on the inner face of said lip.

23. In a lasting machine, the combination with means for pulling an upper over a last successively in different locations along the edge of the last bottom, of a device movable inwardly over the bottom of the last to lay the marginal portion of the upper over a sole and against a lip on the sole in time relation to each upper-pulling opera-

tion, a driver for driving a staple through the upper and the lip in time relation to each overlaying operation, and means movable heightwise of said lip at the end of each driving operation for clinching the legs of each staple on the inner face of the lip.

24. In a lasting machine, the combination with means for pulling an upper over a last successively in different locations along the edge of the last bottom, a device movable inwardly over the bottom of the last to lay the marginal portion of the upper over a sole and against a lip on the sole in time relation to each upper-pulling operation, and means for driving a staple through the upper and the lip in time relation to each overlaying operation, of a pair of awls for forming fastening-receiving holes in the upper and the lip to receive the legs of each staple, cam-controlled means for reciprocating said awls between each overlaying and staple-driving operation, and means for clinching the legs of each staple on the inner face of said lip.

25. A lasting machine having, in combination, means for pulling an upper over a last having a sole thereon provided with an upper-attaching lip, a device movable inwardly over the bottom of the last in a direction inclined toward the bottom face of the last to lay the marginal portion of the upper over the sole and against said lip, means for driving a staple from said device through the upper and the lip, and means for clinching the legs of the staple on the inner face of the lip and for also bending the ends of the staple legs to conform to the angle formed by the lip and the body of the sole.

26. A lasting machine having, in combination, means for pulling an upper over a last having a sole thereon provided with an upper-attaching lip, a device movable inwardly over the bottom of the last in a direction inclined toward the bottom face of the last to lay the marginal portion of the upper over the sole and against said lip, a driver for driving a paper staple through the upper and said lip, and means arranged to engage the ends of the staple legs after the driving operation and to bend them into the angle formed by the inner face of the lip and the body of the sole.

27. A lasting machine having, in combination, means for pulling an upper over a last and for laying its marginal portion inwardly over a sole on the last and against a lip on the sole, a driver for driving a staple through the upper and the lip, and means movable heightwise of the lip at the end of the driving operation for clinching the legs of the staple on the inner face of the lip.

28. A lasting machine having, in combination, means for pulling an upper over a last and for laying its marginal portion inwardly over a sole on the last and against a lip on the sole, a driver for driving a staple through the upper and the lip, means for positioning the shoe by engagement with the lip, and separate means for clinching the legs of the staple on the inner face of the lip after the driving operation.

29. A lasting machine having, in combination, means for pulling an upper over a last and for laying its marginal portion inwardly over a sole on the last and against a lip on the sole, a driver for driving a staple through the upper and the lip, a sole rest for positioning the shoe by engagement with said lip, and means movable relatively to said sole rest at the end of the driving operation for clinching the legs of the staple on the inner face of said lip.

30. A lasting machine having, in combination, means for pulling an upper over a last and for laying its marginal portion inwardly over a sole on the last and against a lip on the sole, a driver for driving a paper staple through the upper and the lip, a sole rest for supporting the lip and for positioning the shoe, said sole rest having its lip-engaging portion slotted to receive the legs of the staple, and a member movable relatively to said sole rest to clinch the legs of the staple on the inner face of said lip.
31. In a lasting machine, the combination with means for pulling an upper over a last and for laying its marginal portion inwardly over a sole on the last and against a lip on the sole, and means for driving a staple through the upper and the lip, of a sole rest for positioning the shoe by engagement with said lip, said sole rest having its sole-engaging end slotted to receive the legs of the staple, a member movable relatively to said sole rest for clinching the legs of the staple on the inner face of the lip, and means for maintaining said member initially in a position to support the lip and for moving the member out of engagement with the lip prior to the staple-driving operation.
32. In a lasting machine, the combination with means for pulling an upper over a last and for laying its marginal portion inwardly over a sole on the last and against a lip on the sole, and means for driving a staple through the upper and the lip, of a sole rest for positioning the shoe by engagement with said lip, said sole rest having its sole-engaging end slotted to receive the legs of the staple, a member slidably mounted in said sole rest and having its lower end portion extending into the slot in said sole rest in position to support the lip of the sole, and means for moving said member away from the sole out of engagement with said lip prior to the staple-driving operation and for moving it toward the sole at the end of the driving operation to clinch the legs of the staple on the inner face of said lip.
33. In a lasting machine, the combination with means for pulling an upper over a last and for laying its marginal portion inwardly over a sole on the last and against a lip on the sole, and means for driving a staple through the upper and the lip, of a sole rest for supporting said lip and for positioning the shoe, said sole rest having its sole-engaging end slotted to receive the legs of the staple, and a member slidably mounted in said sole rest for movement toward the bottom face of the sole in a direction inclined toward the inner face of said lip for forcing the ends of the staple legs into the angle formed by the lip and the body of the sole.
34. In a lasting machine, the combination with means for pulling an upper over a last and for laying its marginal portion inwardly over a sole on the last and against a lip on the sole, and means for driving a staple through the upper and the lip, of a sole rest for positioning the shoe by engagement with said lip, said sole rest having its sole-engaging end slotted to receive the legs of the staple, a pair of awls movable relatively to said sole rest to form holes in the upper and the lip to receive the legs of the staple, a member arranged to extend initially into the slot formed in the sole rest to assist in supporting the lip of the sole in the overlaying operation, and mechanism for moving said member out of engagement with the lip prior to the hole-forming operation and for moving it at the end

of the driving operation in a direction to clinch the legs of the staple on the inner face of the lip and to bend them into conformity to the angle formed by the lip and the body of the sole.

35. That improvement in methods of making turn shoes which consists in assembling on a last shoe materials comprising an upper and a sole having an inside channel and an upper-attaching shoulder with the shoe materials wrong side out, subjecting portions of the upper to lasting strain and while holding each portion in lasted position securing it initially yet permanently to said shoulder by forming fastening receiving holes in the upper and the sole and inserting a paper fastening through the holes in the upper and into the holes in the sole, and thereafter removing the last and turning the shoe.

36. That improvement in methods of making turn shoes which consists in assembling on a last shoe materials comprising an upper and a sole having an inside channel and an upper-attaching shoulder with the shoe materials wrong side out, subjecting portions of the upper to lasting strain heightwise of the last and inwardly over the bottom of the last and while holding each portion in lasted position fastening it initially yet permanently to said shoulder by forming holes in the upper and in the sole in locations below said inside channel and driving a paper staple into said holes, and thereafter removing the last and turning the shoe.

37. That improvement in methods of making turn shoes which consists in assembling on a last shoe materials comprising an upper and a sole having an inside channel and an upper-attaching shoulder with the shoe materials wrong side out, working different portions of the upper successively into lasted relation to the sole and securing each overworked portion permanently in lasted position by a paper staple inserted through the upper and into the sole with the legs of the staple located below said inside channel and with the cross-bar of the staple extending lengthwise of the edge of the sole adjacent to the junction of the shoulder and the sole, thereafter securing said upper to the sole by a line of stitching located substantially in the line of the cross-bars of said staples, removing the last, and turning the shoe.

38. That improvement in methods of making turn shoes which consists in assembling on a last shoe materials comprising an upper and a sole having an inside channel and an upper-attaching shoulder with the shoe materials wrong side out, pulling the upper in different locations heightwise of the last and laying its marginal portion inwardly over the sole and against said shoulder and, while holding the upper against said shoulder in each location, forming fastening receiving holes in the upper and the sole and driving a paper staple into said holes to secure the upper in lasted position, and thereafter removing the last and turning the shoe.

39. That improvement in methods of making turn shoes which consists in assembling on a last shoe materials comprising an upper and a sole having an inside channel and an upper-attaching shoulder with the shoe materials wrong side out, pulling the upper in different locations heightwise of the last and laying its marginal portion inwardly over the sole and against said shoulder and, while holding the upper against said shoulder in each location, forming fastening

receiving holes in the upper and in the sole in locations below said inside channel and driving a paper staple into said holes to secure the upper in lasted position, thereafter securing the upper to the sole by a line of stitching, and removing the last and turning the shoe.

40. That improvement in methods of making shoes which consists in assembling on a last shoe materials comprising an upper and a sole having an inside channel and an upper-attaching shoulder, subjecting portions of the upper to lasting strain and while holding each portion in lasted position fastening it initially yet permanently to said shoulder by inserting paper staples through holes in the upper and into holes previously formed in the sole in locations below said inside channel, thereafter securing the upper to the sole by stitching, and completing the manufacture of the shoe.

41. That improvement in methods of making shoes which consists in assembling on a last an upper and a sole member provided with a lip, working different portions of the upper over the last and securing each overworked portion in lasted position by inserting a staple through the upper and the lip and clinching the legs of the staple on the inner face of the lip and also bending them into conformity to the angle formed by the inner face of the lip and the sole, thereafter securing the upper to the sole by stitching, and completing the manufacture of the shoe.

42. That improvement in methods of making shoes which consists in assembling on a last an upper and a sole member provided with a lip, securing the upper permanently in lasted relation to the sole by forming holes in the upper and the lip, inserting paper staples through the holes in the upper and the lip and clinching the legs of the staples on the inner face of the lip, and then completing the manufacture of the shoe.

43. That improvement in methods of making turn shoes which consists in assembling on a last shoe materials comprising an upper and a sole having an inside channel lip with the shoe materials wrong side out, working different portions of the upper over the last and securing each overworked portion in lasted position by inserting a paper staple through the upper and said lip and bending the legs of the staple toward the sole and also bending them into conformity to the angle formed by the lip and the sole, securing the upper to the sole by stitching passing through the upper and the substance of the sole, and thereafter removing the last and turning the shoe.

44. That improvement in methods of making shoes which consists in assembling on a last shoe materials comprising an upper and a sole having an inside channel lip, pulling the upper over the last and laying its marginal portion inwardly over the bottom of the last and against said lip and, while holding the upper against said lip, forming fastening receiving holes in the upper and said lip, driving a paper staple into said holes and clinching the legs of the staple on the inner face of the lip to secure the upper in lasted position, and then completing the manufacture of the shoe.

45. That improvement in methods of making shoes which consists in assembling on a last shoe materials comprising an upper and a sole member having an inside channel lip, tensioning the upper over the last successively in differ-

ent locations and also laying the margin of the upper successively in different locations inwardly over the bottom of the last and against said lip, and securing each of the overlaid portions of the margin of the upper to the sole, before laying the upper over the bottom of the last in the next succeeding location, by driving a paper staple through the upper and the lip and by the use of a clinching tool bending the legs of the staple toward the bottom face of the sole and in the bending operation compressing the material of the legs of the staple between the tool and the lip.

46. That improvement in methods of making shoes which consists in assembling on a last shoe materials comprising an upper and a sole having an inside channel lip, tensioning the upper over the last successively in different locations and also laying the margin of the upper successively in different locations inwardly over the sole and against said lip, and securing each of the overlaid portions of the margin of the upper to the sole, before laying the upper over the sole in the next succeeding location, by driving a paper staple through the upper and the lip and by the use of a clinching tool bending the ends 25 of the staple legs into conformity to the angle formed by the lip and the sole and compressing the material of the staple legs between the sole and said tool.

47. A shoe having a sole to which the margin 30 of the upper along its opposite sides is secured in lasted condition by staples driven through portions of the upper subjected to strain in the lasting operation and a lip on the sole with the legs of the staples clinched on the inner face of the 35 lip and bent to conform to the angle formed by the lip and the sole.

48. A shoe having a sole to which the margin of the upper along its opposite sides is secured in lasted condition by paper staples driven through 40 portions of the upper subjected to strain in the lasting operation and a lip on the sole with the legs of the paper staples bent toward the base of the lip and flattened against the inner face of the lip.

49. A shoe having a sole to which the margin of the upper along its opposite sides is secured in lasted condition by paper staples driven through portions of the upper subjected to strain in the 50 lasting operation and a lip on the sole with the legs of the staples clinched on the inner face of the lip and bent to conform to the angle formed by the lip and the sole.

50. A shoe having a sole to which the margin of the upper along its opposite sides is secured in 55 lasted condition by paper staples driven through portions of the upper subjected to strain in the lasting operation and a lip on the sole with the legs of the staples clinched on the inner face of the lip and flattened against said face.

51. A shoe having a shouldered sole provided with an inside channel to which the margin of the upper along the opposite sides of the shoe is secured in lasted condition by paper staples driven through portions of the upper subjected to strain in the 65 lasting operation and into the sole in locations below said inside channel with the cross-bars of the staples extending lengthwise of the sole close to the junction of the shoulder and the margin of the sole.

FRED N. LA CHAPELLE.
